UNITED STATES PATENT OFFICE.

ALBERT DESILETS, OF MANCHESTER, NEW HAMPSHIRE, ASSIGNOR TO TRANSFERABLE SAFETY POCKET COMPANY, OF MANCHESTER, NEW HAMPSHIRE, A CORPORATION OF NEW HAMPSHIRE.

POCKET.

Application filed May 5, 1924. Serial No. 711,272.

To all whom it may concern:

Be it known that I, ALBERT DESILETS, a citizen of the United States, residing at Manchester, in the county of Hillsborough and State of New Hampshire, have invented new and useful Improvements in Pockets, of which the following is a specification.

My present invention has reference to a removable or transferable pocket for street 10 car conductors, policemen and the like.

My primary object is the production of a pocket which can be removably received in a trouser pocket, and which has its mouth portion formed of leather to protect the uniform 15 form and is transferable from one to another garment without the employment of a tailor.

A further object is to produce a transferable hip pocket for policemen of a construction to protect the edges of the pocket of 20 the trousers where handcuffs and guns are carried, and also wherein the pocket is provided with a secret compartment for the storage of valuables.

To the attainment of the foregoing and 25 other objects which will present themselves as the nature of the invention is better understood, reference is to be had to the drawings which accompany and which form part of this application.

30 In the drawings:—

Figure 1 is an elevation of the improvement arranged on the coat of a uniform.

Figure 2 is a sectional view approximately on the line 2—2 of Figure 1.

35 Figure 3 is a rear elevation of the detachable or removable pocket.

Figure 4 is a sectional view approximately on the line 4—4 of Figure 3.

Figure 5 is a plan view of one of the fastening elements which may be employed.

Figure 6 is an elevation of a removable and transferable pocket for policemen.

Figure 7 is a sectional view on the line 7—7 of Figure 6.

45 Figure 8 is a fragmentary front elevation of the leather protector or mouth for the pocket.

Figure 9 is a sectional view illustrating a slight modification, in which a secret pocket 50 is provided.

Figure 10 is a front elevation of one of the leather strips providing a portion of the mouth of the pocket.

Figure 11 is a similar view of the second leather strip employed.

Figure 12 is a sectional view on the line 12—12 of Figure 10.

In Figure 1, the numeral 1 designates a portion of a coat for street car conductors or the like, and 2 a pocket in the coat.

The mouth of the pocket 2 of the uniform is soon soiled and the pocket torn by the frequent passage of the hand of a conductor therein.

With my improvement the mouth of the pocket and the pocket itself is amply protected, as is the uniform. The mouth of my improvement is made up of two pieces or strips of leather 3 and 4 respectively. Each of the strips has on its inner edge a centrally arranged extension, 5 and 6, respectively.

When the edges of the members 3 and 4 are brought against each other the extensions 5 and 6 are in lapping relation and are extended at a downward curvature from the said strips 3 and 4. The ends of the strips 3 and 4 are cut angularly, as indicated by the numerals 7 and 8. The angle ends 7 of the strips 3 overlie the ends 8 of the strip 4 and these overlying ends are stitched together.

Stitched to the inner faces of the strips 3 and 4 there are the ends and edges of fabric reinforcing strips 9, which is centrally slotted for the passage of the extensions 5 and 6 therethrough. Embedded between the strips of the reinforcing fabric 85

there are heads 10 of eye members 11. These eye members pass through suitable openings provided in the coat 1, the said openings being arranged around the mouth of the pocket 2.

The eyes are engaged by spring clips 12, as clearly disclosed in Figure 5 of the drawings, and in this manner the leather reinforcing mouth of the removable pocket is detachably secured to the coat.

The detachable pocket proper, indicated by the numeral 13 is stitched, as at 14, to the lower edges of the leather extending strips 5 and 6. The confronting edges of the strip extensions 5 and 6 are also stitched together.

The removable pocket 13 is of a size to be snugly received in the uniform pocket 2 and may be firmly attached thereto in a manner as above described or readily removable therefrom by simply drawing the clips 12 out of the eyes 11.

In Figures 6 and 7 I have illustrated a

slight modification, the leather reinforcing strips being, however, substantially similarly constructed. These strips, indicated by the numerals 15 and 16 have their projecting ends preferably stitched around the mouth of the pocket of a policeman's trousers 17. The angular lapping ends of the strips 15 and 16 are stitched together. The lower strip 16, which in this instance enters the mouth of the pocket has sewed thereon a button 19 to be received through a button-hole 20 in the trousers 17. In this manner it will be noted that two pockets or compartments are provided, the main pocket 21 of the trousers, in which the removable pocket is received, being accessible when the button is released, access to the auxiliary pocket being had through the confronting ends of the leather reinforcing strips 15 and 16. The leather reinforcing strips are illustrated in detail in Figures 10 and 11, while in Figure 12 the edges of the said strips are disclosed.

To remove the auxiliary pocket from the uniform 17 the stitching 22 which attaches the leather mouth of the auxiliary pocket to the uniform is ripped, although the leather reinforcing mouth may be attached by eyes and clips or hooks, as previously described.

In Figure 9 I have illustrated an auxiliary pocket in which the leather mouth or reinforcement comprises strips 23 and 24 substantially similar to those previously described. The lower strip 24 is folded upon itself for the reception of a reinforcing element 50, which is stitched between the said folds. This strip carries a button 25 to be received through a button hole in the coat or trousers of the uniform. The strip 23 has an inner fabric facing 26 in which is embedded the heads 27 carrying eyes 28 designed to be engaged by hooks or clips similar to the clips 12 for holding the same on the uniform. To the outer face of the strip 24 there is stitched the face of a pocket 29. To the edges of the inner face of the pocket 29 there is stitched a fabric sheet 30. The strip divides the pocket 20 into two compartments 31 and 32 respectively. The inner compartment 32 is not accessible through the mouth provided by the leather strips 23 and 24, and therefore is especially adapted for the reception of valuables, as access cannot be obtained thereto until the garment

is removed from the person of the wearer. While I have referred to the strips as constructed of leather it is to be understood that any other like suitable material may be employed.

It is believed that the foregoing description, when taken in connection with the drawings will fully set forth the construction of the improvement and its advantages.

Having described the invention, I claim:—

1. A supplemental, removable and transferable pocket for garments having a mouth portion formed of leather strips, each having lapping ends which are stitched together and having their contacting edges centrally formed with extensions which project downwardly and rearwardly from the strips, a pocket stitched to the said extensions reinforcing fabric stitched to the leather strips and having a central slitted portion to receive the extensions and the pocket therethrough, and fastening means, comprising headed elements having their headed portions pocketed between the reinforcing fabric and the leather strips and having shank portions which project through the reinforcing fabric.

2. A supplementary, removable and transferable pocket for garments including soft leather strips having widened ends which are arranged in lapping relation and which are stitched together, said strips having their inner and confronting edges formed with extensions between the ends of the strips, and the said extensions being directed rearwardly and downwardly with respect to the strips, a pocket having its sides connected respectively to the extensions, said pocket having on its inner face a fabric sheet which is stitched to the edges and to the bottom thereof and which provides an auxiliary pocket, a reinforcing fabric secured to the inner face of the leather strips and which is centrally slitted longitudinally to permit of the strip extensions passing therethrough, means for fastening the auxiliary pocket around the mouth of the pocket of a garment, said means comprising headed elements which are embedded between the reinforcing sheet and the leather mouth of the auxiliary pockets and which have shank portions projecting through said reinforcing sheet.

In testimony whereof I affix my signature.

ALBERT DESILETS.
